GEM-DINITRO CARBAMATES

Karl Klager, Monrovia, Calif., assignor to Aerojet-General Corporation, Azusa, Calif., a corporation of Ohio

No Drawing. Filed July 15, 1957, Ser. No. 672,540

20 Claims. (Cl. 260—482)

This invention relates to new compositions of matter and a method for their preparation. In particular, it relates to carbamates having the general formula:

wherein R and R' are the same or different alkyl groups, and A is an alkylene group.

This application is a continuation-in-part of my pending application, Serial No. 426,901, filed April 30, 1954, now abandoned.

The new compositions of my invention readily undergo hydrolysis to yield their corresponding amino acids, as disclosed in my copending United States patent application, Serial No. 672,539, filed concurrently herewith. The amino acids thus produced readily react with β -geminal polynitro alcohols such as dinitroethanol to produce their corresponding esters. The esters thus produced are excellent high explosives and can be used in any conventional explosive missile, projectile, rocket, or the like, as the main explosive charge. An example of such a missile is disclosed in United States Patent No. 2,470,162, issued May 17, 1949. One way of using the high explosives in a device such as that disclosed in United States Patent No. 2,470,162 is to pack the crystalline explosive in powder form into the warhead of the missile. Alternatively, the crystals can be first pelletized and then packed. A charge thus prepared is sufficiently insensitive to withstand the shock entailed in the ejection of a shell from a gun barrel or from a rocket launching tube under the pressure developed from ignition of a propellant charge, and can be caused to explode on operation of an impact- or time-fuse mechanism firing a detonating explosive such as lead azide or mercury fulminate.

The compounds of the present invention are conveniently prepared by reacting a carboalkoxynitro-containing acid halide with an azide of an alkali or alkaline earth metal and subsequently heating under anhydrous conditions in the presence of an alcohol, in accordance with the general reaction scheme set forth below:

wherein X is a halogen radical, M is an alkali or alkaline earth metal radical, and R, R' and A are as defined above.

The carboalkoxy nitro-containing acid halides employed as starting materials in this invention are prepared by reacting the corresponding acid with a thionyl halide or a phosphorous halide. The acids are obtained by the condensation of the nitronate salt of a nitro-containing ester with a labile hydrogen-containing acid, e.g. acrylic

acid. The reactive carbonyl centers may be reversed in the starting material by condensing the nitronate salt of a nitro-containing acid with a labile hydrogen-containing ester, e.g. methyl acrylate. By condensing appropriate 5 nitronate salts of acids and esters with labile hydrogen-containing acids and esters and reacting the condensation product with a thionyl halide, a wide variety of carboalkoxy nitro-containing acid halides are available as starting materials for the preparation of the amides of this 10 invention.

To more fully illustrate this invention, the following examples are presented. It is to be understood, however, that these examples are presented merely as a means of illustration and are not intended to limit the scope of the 15 invention in any way.

EXAMPLE I

Preparation of dimethyl 4,4-dinitro-7-aza-octanedioate

20 A mixture of 30 gm. 6-carbomethoxy-4,4-dinitrohexanoic acid and 100 ml. freshly distilled thionyl chloride was refluxed for 5 hours in a three-necked flask provided with a stirrer, reflux condenser and thermometer. After allowing the mixture to stand overnight, the excess of thionyl chloride was removed in vacuo to yield 35.5 gm. 25 of a honey-like oil, the 6-carbomethoxy-4,4-dinitrohexanoyl chloride. Without further purification this acid chloride was dissolved in 50 ml. acetone and dropped into a solution of 15 gm. sodium azide in 100 ml. water at a temperature of 20–25° C., within a period of 3 minutes. 30 Stirring was then continued for 45 minutes at the same temperature. The water phase was extracted with chloroform and the extract was washed with aqueous sodium bisulfite, then dried and filtered. After adding 50 ml. of methanol the solution was refluxed for 60 minutes. The 35 chloroform-methanol solution was then concentrated in vacuo until crystals formed. The crystalline dimethyl 4,4-dinitro-7-aza-octanedioate was collected on a Buchner funnel and washed with cold ether. After 2 recrystallizations from methanol and 1 recrystallization from isopropyl ether, 22 gm. of colorless prisms were obtained, M.P. 75° C. The elemental analysis of the product is as follows.

40 Calculated for $\text{C}_9\text{H}_{15}\text{N}_3\text{O}_8$: Percent C, 36.86; percent H, 5.15. Found: Percent C, 37.10; percent H, 5.22.

EXAMPLE II

Preparation of ethyl 7-carbomethoxy-5,5-dinitro-2-aza-heptanoate

50 Ethyl 7-carbomethoxy-5,5-dinitro-2-aza-heptanoate was prepared by reacting 6-carbomethoxy-4,4-dinitrohexanoyl chloride with sodium azide according to the procedure described in Example I. The chloroform mixture was mixed with 50 ml. of ethanol and slowly heated to reflux. 55 After the evolution of nitrogen ceased the heating was continued for 60 minutes. The solvent was then removed by evaporation in vacuo leaving a creamy colored oil which crystallized upon prolonged standing. The crystals were dissolved in absolute ether, decolorized with charcoal and cooled to –20° C. Upon addition of hexane, 60 white crystals, M.P. 39° C., formed.

EXAMPLE III

Preparation of propyl 7-carbomethoxy-5,5-dinitro-2-aza-heptanoate

65 Propyl 7-carbomethoxy-5,5-dinitro-2-aza-heptanoate was prepared by reacting 6-carbomethoxy-4,4-dinitrohexanoyl chloride with sodium azide according to the procedure described in Example I, and heating the resulting 70 organic azide in the presence of propanol. The product, recrystallized from a mixture of ethanol and water, had a melting point of 70–71.5° C.

3

EXAMPLE IV

Preparation of butyl 7-carbomethoxy-5,5-dinitro-2-aza-heptanoate

Butyl 7-carbomethoxy-5,5-dinitro-2-aza-heptanoate was prepared by reacting 6-carbomethoxy-4,4-dinitrohexanoyl chloride with sodium azide according to the procedure described in Example I, and heating the resulting organic azide in the presence of butanol. The product, recrystallized from a mixture of ether and hexane, had a melting point of 30-30.5° C.

The reaction temperatures used in the above examples are completely arbitrary and were selected purely for reasons of convenience. Both higher and lower temperatures can be used without affecting the course of the reaction.

While any of the alkali and alkaline earth metal azides, such as magnesium, potassium, etc. azides, can be used in the practice of my invention, sodium azide is preferred for reasons of cost and availability.

Other members in the new class of compounds of my invention can be prepared by proceeding in accordance with the general reaction scheme and the specific examples presented above. For example, propyl 2-aza-5,5-dinitro-7-carboethoxyheptanoate is prepared by reacting 4,4-dinitro-6-carboethoxy hexanoyl bromide with sodium azide in the presence of propanol; isopropyl 2-aza-4,4-dinitro-6-carboisopropoxy hexanoate is prepared by reacting 3,3-dinitro-5-carboisopropoxy pentanoyl chloride with sodium azide followed by heating in the presence of isopropanol; n-butyl 2-aza-4,4-dinitro-6-carbopropoxy hexanoate is prepared by reacting 3,3-dinitro-5-carbopropoxy pentanoyl chloride with sodium azide followed by heating in the presence of butanol; ethyl 2-aza-5,5-dinitro-8-carboethoxy octanoate is prepared by reacting 4,4-dinitro-7-carboethoxy heptanoyl chloride with sodium azide followed by heating in the presence of ethanol; methyl 2-aza-5-nitro-7-carbomethoxy heptanoate is prepared by reacting 4-nitro-6-carbomethoxy hexanoyl chloride with sodium azide followed by heating in the presence of methanol; and methyl 2-aza-5-methyl-5-nitro-9-carboethoxy nonanoate is prepared by reacting 4-methyl-4-nitro-8-carboethoxy octanoyl chloride with sodium azide followed by heating in the presence of methanol.

It is apparent from the above discussion that any member of the carboalkoxy-aza-nitro ester series disclosed may be prepared by merely reacting an appropriate carboalkoxy-nitro acid in accordance with the teachings of this invention.

I claim:

1. As new compositions of matter, the nitro-containing carbamates having the general formula:

wherein R and R' are lower alkyl radicals and A is a lower alkylene radical.

2. As a new composition of matter, dimethyl 4,4-dinitro-7-aza-octanedioate having the structural formula:

3. As a new composition of matter, ethyl 7-carbomethoxy-5,5-dinitro-2-aza-heptanoate having the structural formula:

4. As a new composition of matter, propyl 7-carbo-

methoxy-5,5-dinitro-2-aza-heptanoate having the structural formula:

5. As a new composition of matter, butyl 7-carbomethoxy-5,5-dinitro-2-2-aza-heptanoate having the structural formula:

15 6. As a new composition of matter, propyl 2-aza-5,5-dinitro-7-carboethoxy-heptanoate having the structural formula:

20 7. As a new composition of matter, isopropyl 2-aza-4,4-dinitro-6-carboisopropoxy-hexanoate having the structural formula:

25 8. As a new composition of matter, n-butyl 2-aza-4,4-dinitro-6-carbopropoxy-hexanoate having the structural formula:

30 9. As a new composition of matter, ethyl 2-aza-5,5-dinitro-8-carboethoxy-octaanoate having the structural formula:

35 10. As a new composition of matter, methyl 2-aza-5,5-dinitro-7-carbomethoxy-heptanoate having the structural formula:

40 11. As a new composition of matter, methyl 2-aza-5,5-methyl-5-nitro-9-carboethoxy-nonanoate having the structural formula:

12. The method of preparing nitro-containing carbamates having the general formula:

which comprises reacting an organic acid halide having the general formula:

wherein X is a halogen radical, R and R' are lower alkyl radicals and A is a lower alkylene radical, with an azide selected from a group consisting of alkali and alkaline earth metal azides, and subsequently heating the resultant organic azide in the presence of an alcohol.

70 13. The method of preparing dimethyl 4,4-dinitro-7-aza-octanedioate which comprises reacting 6-carbometh-

oxy-4,4-dinitrohexanoyl chloride with sodium azide and subsequently heating the resultant organic azide in the presence of methanol.

14. The method of preparing ethyl 7-carbomethoxy-5,5-dinitro-2-aza-heptanoate which comprises reacting 6-carbomethoxy-4,4-dinitrohexanoyl chloride with sodium azide and subsequently heating the resultant organic azide in the presence of ethanol.

15. The method of preparing propyl 7-carbomethoxy-5,5-dinitro-2-aza-heptanoate which comprises reacting 6-carbomethoxy-4,4-dinitrohexanoyl chloride with sodium azide and subsequently heating the resultant organic azide in the presence of propanol.

16. The method of preparing butyl 7-carbomethoxy-5,5-dinitro-2-aza-heptanoate which comprises reacting 6-carbomethoxy-4,4-dinitrohexanoyl chloride with sodium azide and subsequently heating the resultant organic azide in the presence of butanol.

17. The method of preparing propyl 2-aza-5,5-dinitro-7-carboethoxy which comprises reacting 4,4-dinitro-6- 20

carboethoxy hexanoyl bromide with sodium azide, and subsequently heating the resultant organic azide in the presence of propanol.

18. The method of preparing isopropyl 2-aza-4,4-dinitro-6-carboisopropoxy hexanoate which comprises reacting 3,3-dinitro-5-carboisopropoxy pentanoyl chloride with sodium azide and subsequently heating the resultant organic azide in the presence of isopropanol.

19. The method of preparing n-butyl 2-aza-4,4-dinitro-6-carbopropoxy hexanoate which comprises reacting 3,3-dinitro-5-carbopropoxy pentanoyl chloride with sodium azide and subsequently heating the resultant organic azide in the presence of n-butanol.

20. The method of preparing ethyl 2-aza-5,5-dinitro-8-carboethoxy octanoate which comprises reacting 4,4-dinitro-7-carboethoxy heptanoyl chloride with sodium azide and subsequently heating the resultant organic azide in the presence of ethanol.
